(57) **CLAIM**

We claim the ornamental design for a calibration device, as shown and described.

DESCRIPTION

FIG. 1 is a front, right and top perspective view of a calibration device showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of an encircled portion 9 of FIG. 1;

FIG. 10 is an enlarged view of an encircled portion 10 of FIG. 1;

FIG. 11 is an enlarged view of an encircled portion 11 of FIG. 1;

FIG. 12 is an enlarged view of an encircled portion 12 of FIG. 1;

FIG. 13 is an enlarged view of an encircled portion 13 of FIG. 1;

FIG. 14 is an enlarged view of an encircled portion 14 of FIG. 2;

FIG. 15 is an enlarged view of an encircled portion 15 of FIG. 2;

FIG. 16 is an enlarged view of an encircled portion 16 of FIG. 2;

FIG. 17 is an enlarged view of an encircled portion 17 of FIG. 2;

FIG. 18 is an enlarged view of an encircled portion 18 of FIG. 2;

FIG. 19 is another front, right and top perspective view similar to FIG. 1, but showing the arms in a folded state; and, FIG. 20 is another rear, left and bottom perspective view similar to FIG. 2, but showing the arms in a folded state. The broken lines depict portions of the calibration device in which the design is embodied that form no part of the claimed design.
